UNITED STATES PATENT OFFICE.

EMIL G. SCHULTZ, OF MILWAUKEE, WISCONSIN.

BURGLAR ALARM FOR AUTOMOBILES.

Application filed March 28, 1927. Serial No. 179,070.

This invention relates to burglar alarms for automobiles.

Objects of this invention are to provide a novel form of burglar alarm for automobiles which may be applied to the automobile with a minimum of effort and which when so applied is relatively inconspicuous and, consequently, will be unnoticed by the thief.

Further objects are to provide a burglar alarm for automobiles which is designed to blow a whistle whenever the engine is started and which is so constructed that the whistle will continuously sound as long as the engine is running when the device is set in a certain position, and which is also so made that the operator is merely required to step upon a button in order to set the device.

Further objects are to provide a device which when moved into operative position or alarm giving position will automatically lock itself and which may be released only by the insertion and rotation of a key to withdraw the locking plunger.

Further objects are to provide a device which may be readily produced from simple castings, for instance, and which is of extremely simple and rugged construction.

An embodiment of the invention is shown in the accompanying drawings in which:—
30 Figure 1 is a sectional view through the device and through a portion of the automobile floor board to which it is attached;

Figure 2 is a transverse sectional view on the line 2—2 of Figure 1.

Referring to the drawings, it will be seen that the device comprises a casing 1 which is preferably rectangular in contour, although obviously, it may take other shapes, and which is formed of two sections provided with projecting ears 2 which are riveted or bolted together, as indicated at 3 in Figure 2. Each half section is provided with a projecting pipe-like portion 4, as shown in Figure 1, and the extreme ends of these pipe-like portions are preferably split, as indicated at 5. The pipe-like portions are adapted to receive the exhaust pipe 6 and the pipe 7 leading to the muffler.

Clamps 8 surround the pipe-like portions and are drawn together by suitable bolts 9.

The upper part of the casing 1 is provided with an outwardly projecting apertured and internally threaded boss 10 within which a whistle 11 screws. This whistle is preferably pinned in place, as indicated by the reference character 12, to prevent removal.

The upper portion of the casing is closed and is provided with a pair of outwardly projecting ears 13 which are bolted through the floor bottom 14 to the ears 15 of a small 60 casing 16 secured to the upper side of the floor bottom. This casing is provided with a lock 17 equipped with a key slot 18 and with a spring pressed plunger 19. The plunger 19, it will be noted is provided with a 65 bevelled face 20 on its upper side.

Within the casing 1, a slideable valve member 21 is provided, and it will be noted from Figure 2, that this valve-like member consists of a rectangular box-like portion open 70 towards the whistle side of the casing 1 and open at its top. It is provided with a closed bottom 22 which is normally positioned above the pipe-like portions 4 as may be seen from Figure 1. The upper portion of the valve 75 is provided with a transverse member 23 to which is secured the plunger rod or operating rod 24. This plunger rod is provided with an upper notch 25. It is also provided with a head 26 and is surrounded by a spring 27 80 which urges the rod upwardly.

In using the device, it will be apparent that the exhaust gases pass directly through the lower portion of the casing to the muffler and the whistle is cut off by the bottom 22 85 of the valve member. However, when the operator desires to throw the device into operation, as when he leaves the car, for example, he merely steps upon the button 26 and depresses the plunger 24. This moves 90 the valve into its lower dotted line position, and it will be seen that the exhaust pipe is then thrown into communication with the whistle and is cut off from the pipe 7, leading to the muffler. The spring pressed plunger 95 19 of the lock snaps into the notch 25 and locks the plunger 24 in depressed position. The flat face of the plunger 19 contacts with the flat face of the notch 25 and obviously prevents upward withdrawal of the plunger. 100 The apparatus, therefore, gives a very loud continuous signal, as long as the engine is running.

When the operator returns to his car, all that is necessary to throw the device into inoperative position is to insert his key into the key slot 18 and retract the plunger 19. This releases the plunger rod 24 and the spring draws the valve into its full line or uppermost position, as shown in Figure 1. 110

If desired, a lower notch corresponding to the notch 25, may be formed in the plunger.

er rod 24, so as to provide a second notch into which the plunger 19 of the lock snaps. In view of the fact that the plunger 19 has a bevelled upper face 20, it is apparent that 5 this locking plunger will be cammed out of the lower notch when the operator steps upon the button 26. Such a construction may be resorted to merely for the purpose of frictionally holding the plunger rod 24 in elevated position, although usually the spring 10 27 will be found sufficient.

It is thus clear that a very simple and easily produced device has been provided which may be instantly thrown into operation without 15 the use of the lock key, and which may be readily released by means of the lock key carried by the operator.

Further, it is apparent that the device may be very readily installed, as it is merely necessary to cut out a section of the exhaust pipe 20 and slip the ends of the apparatus over the ends of the pipe, as shown in Figure 1 and to bolt the lock portion through the floor of the automobile to the casing flanges.

25 Although the invention has been described in considerable detail, such description is intended as illustrative rather than limiting as the invention may be variously embodied and as the scope of such invention is to be determined as claimed.

I claim:

1. In an automobile, the combination of an exhaust pipe, a two-part casing having its two parts riveted together and having an inlet portion connected to the exhaust pipe and having a pair of outlet openings, a muffler pipe connected to said casing at one of the outlet portions and in line with the exhaust pipe, a sounding device connected to said casing at the other of said outlet openings, and a slide valve carried within said casing and slidable to either of two positions, said slide valve having a closed bottom positioned

above the exhaust pipe and muffler pipe when in one position, and having a hollow interior 45 placing the sounding device in communication with the exhaust pipe when in another position, said valve and said casing being of rectangular construction.

2. The combination of an automobile having a floor board, an exhaust pipe and a muffler pipe and a burglar alarm device comprising a two-part casing having its two parts riveted together and having an inlet and an outlet in line with each other and connected 50 respectively to said exhaust pipe and said muffler pipe, said casing having a second outlet, a whistle secured to said casing and communicating with said second outlet, a slideable valve carried within said casing and 55 having a valve rod projecting upwardly therefrom and through the floor board, a lock secured to the upper side of the floor board and having a spring pressed plunger, said valve rod having a notch therein for the 60 reception of said plunger when said valve is moved to a position placing the whistle in communication with the exhaust pipe, a spring urging said valve rod upwardly to place the exhaust pipe and muffler pipe in 65 communication, and a knob carried by the upper end of said valve rod, whereby said knob may be depressed by the operator and said valve rod will be latched by the plunger 70 of said lock to hold said valve in the position 75 placing the whistle in communication with the exhaust pipe, said casing having a rectangular interior and said valve being rectangular and fitting the interior of said casing.

In testimony that I claim the foregoing I have hereunto set my hand at Milwaukee, in the county of Milwaukee and State of Wisconsin.

EMIL G. SCHULTZ.
